SCHOOL DESK OR THE LIKE

Carl W. Sundberg and Montgomery Ferar, Southfield,
Mich., assignors to American Seating Company, Grand Rapids, Mich., a corporation of New Jersey
Filed Jan. 10, 1963, Ser. No. 73,125

Term of patent 14 years

(Cl. D33—11)

We claim:
The ornamental design for a school desk or the like,
substantially as shown.
